Geo. P. Kimmel.
ATTORNEY.

UNITED STATES PATENT OFFICE

JOSEPH J. SCHMITT, OF ALGOMA, WISCONSIN

FOLDING CHAIR

Application filed February 26, 1929. Serial No. 342,708.

This invention relates to folding chairs and has for its object to provide, in a manner as hereinafter set forth, an article of such class so constructed and arranged whereby the elements thereof will be nested together in a compact form when the chair is folded.

A further object of the invention is to provide, in a manner as hereinafter set forth, a chair of the class referred to including a pivoted seat and pivoted rear legs capable when folded to be positioned respectively, within the back and between the front legs of the chair when the latter is folded.

A further object of the invention is to provide, in a manner as hereinafter set forth, a foldable chair including a seat carried by a pair of sliding pivots acting as means to couple the seat with the front legs of the chair and further sliding in such legs when the chair is extended and contracted.

A further object of the invention is to provide, in a manner as hereinafter set forth, a folding chair including a pair of front and a pair of rear legs pivotally connected together, and a brace for the rear legs constituting a spacing means between the front and rear legs and supporting means or bearings for the pivots between said legs.

A further object of the invention is to provide, in a manner as hereinafter set forth, a new and improved bracing element for the rear legs of the chair.

A further object of the invention is to provide, in a manner as hereinafter set forth, a chair of the class referred to having a pair of slidable pivots between the seat and front legs and a means for bracing and connecting the front legs together with such means acting as a support for the seat when the chair is extended.

A further object of the invention is to provide, in a manner as hereinafter set forth, a folding chair including a back member having end extensions for coupling to the side elements of the chair and with each of said elements forming a side rail of the chair back and a front rail of the chair.

Further objects of the invention are to provide, in a manner as hereinafter set forth, a foldable chair which is simple in its construc-

tion and arrangement, strong, durable, compact, readily extended and contracted, capable of being folded in an unusually compact manner, readily assembled and comparatively inexpensive to manufacture.

With the foregoing and other objects in view the invention consists of the novel construction, combination and arrangement of parts as hereinafter more specifically described, and illustrated in the accompanying drawings wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a vertical sectional view of a folding chair in accordance with this invention and with the chair extended, and further illustrating in dotted lines the chair partly folded.

Figure 2 is a rear elevation of the chair when folded.

Figure 3 is a fragmentary view, partly in section of the chair when extended.

Figure 4 is a section on line 4-4 Figure 3.

Figure 5 is a section on line 5-5 Figure 3.

Figure 6 is a detail on line 6-6 Figure 2.

The chair includes a pair of oppositely disposed channel shaped elements of appropriate length and which are referred to generally at 8 and 9. Each of said elements constitutes a front leg 4 and a side rail of the back of the chair. That portion of each of said elements which constitutes a front leg for the chair is indicated at 10 and the portion which provides a side rail of the back of the chair is indicated at 11. The channel formed by each element 8, 9 is indicated at 12 and is co-extensive with such element.

The chair further includes a pair of rear legs 13, 14 and each of which is formed on its inner face with a channel 15 extending from a point removed from the upper end of the leg to the lower end thereof. The upper end of each rear leg is flat as indicated at 17.

The lower end of each of the legs of the chair is provided with a foot piece 18 of a

100

length slightly greater than the width of the leg and which closes the lower ends of the channels formed in the legs.

The legs 13, 14 are arranged between the legs 10. Each rear leg is mounted on a pivot 19 positioned at a point above but in proximity to the transverse median of the rear legs. The pivots 19 extend through the front legs 10 and rear legs 13, 14 and their ends are upset. Welded or otherwise secured to the front of the rear legs is a brace member 20 having angularly disposed ends 21 which are interposed between the rear legs and front legs and through which extend the pivots 19. The ends 21 constitute spacing means between the rear and front legs. The bracing member 20 is rectangular in cross section. A channel shaped brace member 22 having right angularly disposed end flanges 23 is positioned between the rear legs 13, 14 near the lower ends thereof.

Holdfast devices 24 extend through the flanges 23 for fixedly securing the brace member 22 to the rear legs.

The lower ends of the front legs are connected together by a brace member 25 having angle shaped ends 26 which abut against the legs 10 and are fixedly secured therewith by holdfast devices 27 extending through the ends 26. The elements 8, 9 at the point of emergence of the front legs 10 with the side rails 11 have interposed therebetween a combined seat support and brace member referred to generally at 28 and which is formed of an intermediate part 29 and a pair of end parts 30. The end parts are oppositely disposed and curve downwardly with respect to the intermediate part 29. Each end part 30 terminates in a right angularly disposed flange 31 for positioning against and extending across the channel formed in the member 8 or 9. Positioned in the channels of the elements 8, 9 and opposing the flanges 31 are filler blocks 32 provided with openings 33 which register with openings 34, 35 formed in the flanges 31 and elements 8, 9.

Holdfast devices 36 extend through said registering openings for fixedly securing the member 28 between and to the elements 8, 9. The flanges 31 are forwardly directed with respect to the intermediate portion 29 and the latter is positioned rearwardly with respect to the elements 8, 9. See Figure 3. The intermediate portion 29 of the member 28 provides a support for the seat which will be presently referred to.

The chair further includes a seat comprising a frame 37 having its body of angle-shaped cross section to provide a vertical and a horizontal portion 38, 39 respectively. The horizontal portion extends inwardly from the lower end of the vertical portion. The frame is formed of a rear, a front and a pair of sides integral with each other.

Secured upon the horizontal portion 39 is

a bottom member 40 of an area to be spaced from the sides of the frame 37 a sufficient distance to provide a small clearance for a purpose to be presently referred to. The clearance is indicated at 41. Mounted on the bottom member 40 is a cushion 42 having its covering 43 extended to enclose the member 40 at the edges of the latter.

The sides of the frame 37 at a point between the vertical median and rear end of each side is formed with an opening 44 for the passage of a pivot 45, the latter having its inner end upset to provide a head 46 which is positioned in the clearance 41 and opposes the inner face of a side of the frame 37. The outer end of the pivot 45 is fixed to a block 47 which is slidably mounted in the channel 12. The blocks 47 provide for slidably connecting the seat to the side rails of the back of the chair and the headed pivots 45 provide means to enable the seat pivoting relative to the blocks 47 when the chair is extended or contracted. The head 46 of the pivot 45 provides for coupling the seat to the blocks 47. When the chair is extended the seat is supported by the portion 29 and the blocks 47 are spaced from the flanges 31. See Figure 4. This prevents any binding action.

The chair also includes a back provided by the side rails 11, in connection with a back or rest member 48 which is secured between the upper ends of the rails 11. The back or rest member 48 is of arcuate form and projects rearwardly with respect to the upper ends of the rails 11. The member 48 is provided at its top and bottom edges with rearwardly extending flanges or beads 49. The member 48 at each end is formed with a pair of rearwardly disposed extensions 50 each bent upon itself. The extensions 50 are positioned in the channels 12 and fixedly secured to the rails 11 by the holdfast devices 51. The forward face of the member 48 is a substantial continuation of the rear face of the front flange 52' of the elements 8, 9. The member 48 projects from said flanges 52' and the extensions 50 snugly engage the walls of the channels of the rails 11.

The elements of the chair, other than the bottom member 40, cushion 42 and covering 43 are constructed of metallic material of the desired weight.

The flat upper ends 17 of rear legs 13, 14 oppose the outer faces of the sides of the frame 37 and are pivotally connected thereto, as at 52, in proximity to the front of frame 38.

The blocks 47 project a substantial distance inwardly from the elements 8, 9, see Figures 4 and 5, and act as spacing means between the rear portion of the seat and elements 8, 9. This prevents any possibility of the seat at its rear being shifted toward either one of the elements 8, 9.

It is thought the many advantages of a

folding chair, in accordance with this invention can be readily understood, and although the preferred embodiment of the invention is as illustrated and described, yet it is to be understood that changes in the details of construction can be had which fall within the scope of the invention as claimed.

What I claim is:

1. A folding chair comprising front legs, rear legs, channel-shaped side rails forming upper continuations of the front legs, pivotal connections between the front and rear legs intermediate their ends, a back member secured to said side rails, a seat pivoted near its front to the top of the rear legs, blocks slidably mounted in the channels of and projecting inwardly from said rails, and pivotal connections between said blocks and said seat in proximity to the rear of the latter, said pivotal connections fixed to said blocks, extending into said seat and provided with heads for coupling the seat to the blocks.

2. In a folding chair, front and rear legs, pivot means for said legs intermediate the ends thereof, and a brace connecting the rear legs together and provided with angularly disposed end portions, said end portions providing means for spacing the rear legs from the front legs and bearings for the pivot means between the front and rear legs.

3. A folding chair comprising a pair of front legs, a pair of rear legs arranged between said front legs and an independent pivot connection between each front and corresponding rear leg, a brace connecting the rear legs and provided with angularly disposed portions providing spacing means between the front and rear legs, said means having said independent pivot connections extending therethrough.

4. In a folding chair the combination of an upstanding seat back having channel-shaped side rails, a seat for folding between said rails and including a seat member and a frame surrounding said member, said frame including a pair of sides, a front and a rear, said seat member spaced from said sides to provide clearances, said sides in proximity to the rear ends thereof provided with openings, blocks slidably mounted in the channels of said rails, and headed pivots extending through said openings, fixed at their outer ends to said blocks and having the heads positioned in said clearances and opposing the inner faces of said sides whereby the seat is coupled with the blocks.

5. In a folding chair, a seat, a pair of front legs, side rails forming continuations of said legs and of channelled contour, rear legs, pivotal connections between the rear legs and said seat, blocks slidably mounted in the channels of said rails, pivotal connections between said seat and said blocks, a combined seat support and brace for said front legs and including an intermediate portion for support-

ing said seat and of a length greater than the width of the chair seat, said combined support and brace further including a pair of down-curved end portions, each terminating in a forwardly directed flange for positioning against and for securing to the inner sides of said front legs, and said intermediate portion spacing said blocks from the point of connection between the combined seat support and brace and said front legs.

6. In a folding chair, the combination with a pair of front and a pair of rear legs, said front legs extending above the rear legs, means for pivotally connecting the front legs to the rear legs below the upper ends of the latter, said front legs being of channel shaped cross section, a chair seat pivotally connected to the top of the rear legs and slidably connected to the front legs within the channels of the latter above the pivotal connections between said legs, a combined support for the seat and brace for the front legs including an intermediate portion for supporting the seat and a pair of down curved end portions each terminating in a forwardly directed flange secured against the inner side of a front leg, and filler blocks positioned in the channels of the front legs and secured to said seat.

In testimony whereof, I affix my signature hereto.

JOSEPH J. SCHMITT.
